COMBINATION CLOTHESLINE TIGHTENER
AND JOINER

Jose Adams, Los Angeles, Calif.

Application October 8, 1949, Serial No. 5,375

Term of patent 3½ years

(Cl. D49—1)

To all whom it may concern:

Be it known that I, Jose Adams, a subject of the King of Great Britain, residing at Los Angeles, County of Los Angeles, State of California, have invented a new, original, and ornamental Design for a Combination Clothesline Tightener and Joiner, of which the following is a specification, reference being had to the accompanying drawing, forming a part thereof.

I claim:

The ornamental design for a combination clothesline tightener and joiner, as shown.

JOSE ADAMS.
